UNITED STATES PATENT OFFICE.

KNUT S. NYGAARD, OF MEKINOCK, NORTH DAKOTA.

LOCKING DEVICE.

1,187,771.

Specification of Letters Patent. Patented June 20, 1916.

Application filed April 22, 1916. Serial No. 92,986.

To all whom it may concern:

Be it known that I, KNUT S. NYGAARD, a citizen of the United States, residing at Mekinock, in the county of Grand Forks and State of North Dakota, have invented 5 certain new and useful Improvements in Locking Devices, of which the following is a specification, reference being had to the accompanying drawings.

10 This invention relates to certain improvements in locking devices and has relation more particularly to a device of this general character especially designed and adapted for use in connection with a gate, 15 and it is an object of the invention to provide a novel and improved device of this general character which may be operated with convenience and facility by one hand in order to enable the driver of a vehicle 20 to readily manipulate the device.

It is also an object of the invention to provide a novel and improved locking device which is especially adapted for use in connection with a frameless wire gate and 25 which serves to retain the wires of the gate taut when the locking device is operatively engaged with the gate.

30 The invention consists in the details of construction and in the combination and arrangement of the several parts of my improved locking device whereby certain important advantages are attained and the device is rendered simpler, less expensive and otherwise more convenient and advantageous for use, all as will be hereinafter 35 more fully set forth.

The novel features of the invention will hereinafter be definitely claimed.

40 In order that my invention may be the better understood, I will now proceed to describe the same with reference to the accompanying drawings, wherein—

45 Figure 1 is a view in elevation illustrating a locking device constructed in accordance with an embodiment of my invention in applied position and maintaining a frameless wire gate in closed adjustment; Fig. 2 is an enlarged view in top plan of my locking device as herein embodied, the 50 coacting post being shown in section; and Fig. 3 is a view in perspective of my improved locking device as herein set forth.

55 As disclosed in the accompanying drawings, A denotes a gate post to which my improved locking device D is operatively engaged.

G denotes a frameless wire gate including the vertical end bar B with which the locking device D is adapted to coact, and L denotes a loop member permanently secured to the lower end portion of the post A and through which the lower part of the bar B is adapted to be directed when the gate G is in closed position, as is particularly illustrated in Fig. 1 of the accompanying drawings.

60 As herein embodied, my improved locking device D comprises a plate 1 adapted to be extended transversely across a side face of the post A and having one extremity provided with the extension 2 adapted to overlie the rear end of the post A, while the opposite extremity of the plate 1 is provided with the outwardly directed extension 3 65 substantially at right angles to the plate 1.

70 Suitably secured to and overlying the extension 2 is a plate 4 which extends beyond the plate 1, and supported by the extended portion of the plate 4 and the extension 3 is the endwise movable rod 5 having its forward end provided with the plate or head 6 which is substantially horizontally disposed and which extends beyond opposite sides of the rod 5. The rod 5 is constantly urged 75 forwardly by the expandable member or spring 7 encircling the rod 5 and having its one end bearing against the extended portion of the plate 4 and its opposite end bearing against the stop pin 8 directed through the rod 5 and which limits the outward 80 movement of the rod 5 by contact with the extension 3.

85 Rotatably supported by the plate 4 is the shaft 9 which extends beyond the plate 1 and said shaft 9 is provided with a crank 95 10 with which is operatively engaged the free extremity of the shank 11 of the locking member 12, said locking member 12 being herein disclosed as substantially semicircular in form. The shank 11 is directed 100 through the vertically disposed slots 14 and 15 produced respectively in the extension 3 and the head or plate 6, said slots 14 and 15 being of such a length as to offer no obstruction to the endwise movement imparted to the shank 11 by the crank 10 upon rotation of the shaft 9.

105 As is particularly illustrated in Fig. 2, I have coacting with the opposite extremities of the shaft 9 the operating handles 16, although I do not wish to be understood as limiting myself to any particular means for 110

imparting the requisite rotation to the shaft, although it is preferred that an operating means coact with the opposite ends thereof so the requisite movement may be imparted to the shank 11, at either side of the gate or fence.

It will be perceived that as the crank 10 moves forwardly the locking member 12 will be caused to separate a sufficient distance relative to the head or plate 6 to permit the bar B to be engaged within the locking member 12. It will also be self-evident that the rearward movement of the crank 10 will retract the shank 11 and in addition to moving the locking member 12 inwardly relative to the head or plate 6, will tighten or draw taut the wires W included in the gate G.

The extended portion of the plate 4 is provided with the rearwardly inclined resilient lip 17 which coacts with the crank 10 to prevent retrograde movement thereof under the influence of the strain imposed upon the shank 11 by the gate G, but it will be at once perceived that the resiliency of the lip 17 will readily permit the crank 10 to pass thereover when the shaft 9 is rotated to move the crank 10 upwardly and rearwardly to effect a locking action.

When it is desired to release the device from operative engagement with the bar B, the shaft 9 is rotated in a direction to carry the crank 10 downwardly until the same has passed a horizontal center whereupon the strain imposed upon the shank 11 by the gate G will result in the requisite separation between the locking member 12 and the plate 6 as to permit the bar B to be removed from operative engagement with the locking member 12. It will also be understood that a locking action may be had by rotating the shaft 9 in a direction to cause the crank 10 to move downwardly and upwardly until it is past a horizontal center whereby the strain of the gate G will maintain the crank in contact with the lip 17.

The free extremity of the locking member 12 is adapted to overlie an end of the head or plate 6 and in order to limit the inward movement of the shank 11 independently of said head or plate 6, I provide the shank 11, at a point in close proximity to the locking member 12, with the shoulder 18 adapted to contact with the head or plate 6 as is particularly disclosed in Fig. 3.

It will be readily appreciated that the spring 7 serves to cause the head or plate 6 to be engaged with the bar B opposite to that engaged by the locking member 12, and it will also be noted that as the shank 11 is moved rearwardly to tighten the wires W, the spring 7 will permit the head or plate 6 to yield during such operation.

From the foregoing description, it is

thought to be obvious that a locking device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A lock of the character described including a hook member supported for reciprocatory movement, means for operating said hook member, a plate slidably engaged with the hook member, and means for constantly forcing said plate outwardly.

2. A lock of the character described including a hook member supported for reciprocatory movement, means for operating said hook member, a plate slidably engaged with the hook member, means for constantly forcing said plate outwardly, and means carried by the hook member coacting with the plate for limiting the outward movement of the plate.

3. A lock of the character described comprising a base plate adapted to be secured to an object, a shaft carried by said base plate, a crank on said shaft, a hook member operatively carried by the crank, a lip extending from said base plate to be engaged by the crank to retain the hook member in an operative position, and means for rotating said shaft.

4. A lock of the character described comprising a base plate adapted to be secured to an object, a shaft carried by the said base plate, a crank formed on said shaft, a rod connected at one end of the crank and having its opposite end formed into a hook, a yieldable lip carried by the base plate to be engaged by the crank to limit movement of the rod in one direction, means for rotating said shaft and plunger, and means coöperating with said hook member for the purpose set forth.

5. A lock of the character described comprising a base plate having extensions carried thereby, a plunger rod extending through openings in said extensions, a stop member carried by said rod, an expansion spring surrounding the rod and abutting the member and one of the extensions to hold the rod normally at its outermost limit of movement, a head carried by said rod, a hook member, means for operating said hook member, said head being provided with an elongated slot, said hook member being extended through said slot,

and means carried by said hook member for abutting relation with the head to prevent movement of the head toward the hook member past a predetermined point.

- 5 6. A lock of the character described comprising a base plate, extensions formed on said base plate one of said extensions being provided with an elongated slot and a polygonal shaped opening, the other of said 10 extensions being provided with a polygonal shaped opening in alinement with a first-mentioned opening and with a lip, a shaft carried by said base plate, a crank formed on said shaft, a rod connected with said 15 crank and extending through the elongated slot, a rod extending through said alined

openings, an expansion spring acting on said rod to force the same normally to its outermost limit of movement, a head carried by said rod, said first-mentioned rod 20 being extended through said head and formed into a hook, means to limit outward movement of the head past a predetermined point with respect to the hook and means for rotating said shaft for the purpose set 25 forth.

In testimony whereof I hereunto affix my signature in the presence of two witnesses.

KNUT S. NYGAARD.
